Term of patent 14 years

Int Cl. D17—04

U.S. Cl. D56—1 E

FIG. 1 is a rear, top and right side perspective view of a footboard for pedal-operated percussive musical instruments showing my new design;

FIG. 2 is a top plan view;

FIG. 3 is a bottom plan view;

FIG. 4 is a left side elevational view;

FIG. 5 is a rear elevational view;

FIG. 6 is a view similar to FIG. 1 of a second embodiment of the footboard for pedal-operated percussive musical instruments wherein there is an aperture in place of the toe piece; and

FIG. 7 is a top plan view thereof.

The side not shown in FIG. 4 is the mirror image of the side shown therein.

The dominant features of the design reside in the portions thereof viewed from above, not in the showings of the bottom plan view of FIG. 3.

I claim:

The ornamental design for a footboard for pedal-operated percussive musical instruments, substantially as shown and described.
